[57] **CLAIM**

The ornamental design for a automatic towel rinsing machine, as shown and described.

DESCRIPTION

FIG. 1 is a perspective view of an automatic towel rinsing machine showing my new design.

FIG. 2 is a front elevational view thereof.

FIG. 3 is a left side elevational view thereof.

FIG. 4 is a top plan view thereof.

FIG. 5 is a rear elevational view thereof.

The appearance of the right-hand side thereof is a mirror image of the left-hand side shown in FIG. 3 except that the three protruding elements and bar immediately above them are absent.

The bottom is without ornamentation.
